UNITED STATES PATENT OFFICE.

CHARLES N. JACKSON, OF NEW YORK, N. Y.

LEDGER AND STATEMENT POSTING MEANS.

1,324,504.

Specification of Letters Patent.

Patented Dec. 9, 1919.

Application filed December 9, 1918. Serial No. 265,858.

To all whom it may concern:

Be it known that I, CHARLES N. JACKSON, a citizen of the United States of America, residing at New York, N. Y., have invented 5 a new and useful Ledger and Statement Posting Means, of which the following is a specification.

My invention relates to certain improvements whereby the posting of ledger and 10 statement is simultaneously effected, the objects of the invention being to accomplish such results in a simple and effective manner which will be adaptable to the present day systems of bookkeeping.

15 The invention in brief consists of a carrier designed to support both the ledger and statement sheets with a suitable interposed transfer medium so that entries on the ledger will be automatically transferred to the statement, provision being made for supporting the statement in such adjusted positions on the carrier to suit the preceding 20 entries on the ledger.

The various features of the invention, 25 advantages and methods of use will become apparent as the specification proceeds and will be clear from inspection of the accompanying drawing, wherein the invention is shown embodied in a practical commercial 30 form.

In said drawing:

Figure 1, is a face view of the complete device, with the corners of the sheet broken away to expose the sheets therebeneath.

35 Fig. 2, is a perspective view of the carrier element.

Fig. 3, is a similar view of a typical form of statement sheet.

In the illustration 5 designates the ledger 40 sheet which may be of the form now employed in bookkeeping systems where the posting is done on typewriting machines. This ledger sheet differs however from the usual ledger sheet of such systems in that 45 it is provided at the right hand margin thereof with a column 6 of suitable indices, such as the numbers illustrated.

7 designates the statement sheet shown as 50 conforming in general respects to the usual monthly statement but differing like the ledger sheet, in that it is provided at the right hand margin and above the posting line 8, with a column 9 of indicia forming a unit or multiple of the long column on the 55 ledger sheet. In this particular illustration the unit chosen is 10, the column of indicia

on the statement sheet consisting therefore of the numbers 1 to 10.

The carrier is shown as made up of a backing 10 and a supporting sheet 11, said 60 supporting sheet being made fast at its upper edge to the upper edge portion of the backing and free from the backing for the balance of its length. The backing is of the same approximate size as the ledger sheet. 65

The ledger sheet is supported on the face of the carrier by means consisting in the illustration of a pocket 12 extending across the lower edge portion of the backing and designed to receive the entire lower edge of 70 the ledger sheet and corner pockets 13 at the upper corners of the backing to receive the upper corners of the ledger sheet to thereby lock the ledger sheet in position on the carrier. 75

The statement sheet is held in various adjusted positions on the carrier by folding and inserting the upper edge portion of the same in one of the slits 14 provided in the supporting sheet. These slits are spaced 80 apart a distance equal to the unit chosen, as above described—in this case the distance being ten lines.

Means are provided for effecting the transfer of the impressions from the ledger 85 sheet to the statement sheet, such means consisting in the disclosure of a transfer sheet 15 of carbon or the like, interposed between the back of the ledger sheet and the face of the statement sheet and secured for convenience along its upper edge to the face of the supporting sheet 11. 90

As an illustration of the use of the device the last charge for the preceding month is shown as entered on line 5 of the ledger 95 sheet. Consequently the next entry for the current month will be made on line 6. The new statement sheet should therefore be positioned on the carrier so that the head of the statement sheet will register with line 6 on the ledger sheet. This registration or collation is automatically effected by folding the statement sheet on a line corresponding with "5" in the index column thereof as indicated by the dotted line 16 in Fig. 3 105 and then inserting this folded upper portion of the statement sheet in the upper slit of the carrier. This condition is illustrated in Fig. 1 from which it will be seen that by these simple means the statement sheet 110 is accurately positioned on the carrier so that the next entry thereon will appear at

the head of the sheet. If the last entry on the ledger sheet were on line 15 instead of on line 5, the statement sheet would be folded as before, but in this instance, would be 5 engaged with the second slit on the carrier which, as before described, is spaced ten lines below the first slit. Similarly if the last ledger entry were on line 25, the statement, folded as before, would be engaged 10 in the third slit or twenty lines below the first slit. These simple means thus enable practically "automatic" registration of the statement with the ledger sheet.

The statement sheet may be of relatively 15 light paper, such as customarily employed and the ledger sheet and carrier sheets may be of somewhat heavier stock to stand the necessary wear and tear, but the stock is selected so that the device as a whole, while 20 possessing a certain amount of stiffness to facilitate handling and filing the same, will at the same time, be relatively flexible so as to feed properly through the typewriting machine. It will be noted that the layers of 25 paper are substantially equal throughout, which causes the device to feed evenly through the typewriting machine and insures uniform printing impressions.

I claim:—

30 1. In ledger and statement posting, a ledger sheet, a statement sheet, a carrier provided with a pocket for receiving and holding the ledger sheet in position thereon and with means for holding the statement 35 sheet in various adjusted positions beneath the thus supported ledger sheet and means for effecting the transfer of an impression from the ledger sheet to the statement sheet.

2. In ledger and statement posting, a carrier provided with means for supporting a statement sheet in various adjusted positions and with a pocket for receiving and supporting a ledger sheet on the carrier over the thus positioned statement sheet, said carrier 45 further having transfer means for effecting the transfer of an impression from the ledger sheet to the statement sheet.

3. In ledger and statement posting, a statement sheet, a carrier having a plurality 50 of slits spaced apart certain definite units of measurement and adapted to receive the statement sheet to support the same in such various spaced positions on the carrier, a ledger sheet associated with the carrier and 55 overlying the statement sheet, and means for

effecting the transfer of an impression from the ledger sheet to the statement sheet beneath the same.

4. In ledger and statement posting, a ledger sheet, a carrier provided with opposed pockets receiving opposite edge portions of the ledger sheet to thereby position and hold the ledger sheet on the face of said carrier, a statement sheet, means for securing said statement sheet, in various 60 adjusted positions beneath the ledger sheet and a transfer sheet interposed between the back of the ledger sheet and the face of the statement sheet.

5. In ledger and statement posting, a statement sheet, a carrier having a series of slits arranged in certain definite spaced relation and adapted to receive the statement sheet to position the same in such several definite locations on the carrier, a ledger 75 sheet, means for supporting said ledger sheet in position on the carrier over the statement sheet and means for effecting the transfer of an impression from the ledger sheet to the statement sheet.

6. A combination like that set forth in claim 5, wherein the ledger sheet is provided with a column of indicia, the spacing of the slits in the carrier is in the order of certain definite units of said column and the 85 statement sheet is provided with a column of indicia equivalent to one of said units of spacing.

7. Combined ledger and statement posting means, comprising a ledger sheet, a statement sheet, a carrier having means for supporting said statement sheet in various adjusted positions thereon, said carrier having a pocket extending across the lower edge thereof to receive the lower edge of the 95 ledger sheet and corner pockets at the upper edge thereof to receive the upper corners of said ledger sheet and means for effecting transfer of impressions from the ledger sheet to the statement sheet.

8. In ledger and statement posting, a carrier having a series of slits spaced in certain definite relation and adapted to receive a statement sheet to position the same in such various locations on the carrier, and 105 transfer means on the carrier for effecting the transfer of an impression from an overlying ledger sheet to a statement sheet thus positioned on the carrier.

CHARLES N. JACKSON.
